UNITED STATES PATENT OFFICE.

CARMELO DI MARTINO AND EDWARD LINDQUIST, OF PATERSON, NEW JERSEY.

COIN-CONTROLLED MECHANISM.

Original application filed January 13, 1926, Serial No. 80,940. Divided and this application filed May 27, 1926. Serial No. 112,008.

Our present application is a division of our application for Letters Patent for improvements in vending machines Serial No. 80,940, and the invention herein set forth 5 consists in improved coin-controlled mechanism for use in connection with vending machines and the like.

Fig. 1 is a front elevation of a vending machine embodying our improvements;

10 Fig. 2 is a horizontal section on the line 2—2 in Fig. 1 of the right hand portion of the machine;

Fig. 3 is a right side elevation;

15 Fig. 4 is a fragmentary section on line 4—4, Fig. 3;

Fig. 5 is a left side elevation of a fragment of a machine, partly broken away;

Fig. 6 is a fragmentary section on line 6—6, Fig. 3;

20 Fig. 7 is a sectional detail of the coin chute; and

Fig. 8 shows the door latch.

Briefly describing the vending machine shown, the same being fully set forth in 25 detail in our aforesaid application: The case of the machine has two side walls 1, a front wall 2 with an opening 2^a therein, top and bottom walls 3 and 4, top and bottom cross braces, 5 and 6, and a door 7 occupying 30 the opening 2^a and adapted to swing from closed to open position downwardly on a horizontal axis at its lower or pivoting edge. The case contains, suitably journaled in 5 and 6 on a vertical axis, a semi-circular 35 shield 9 and also, suitably pivoted therein, a tray or carrier 11 (Fig. 3) which is pivoted at 12 in the case and when the door is open and the shield is in the position shown in Fig. 2 will be shifted in a horizontal 40 plane forwardly through the door opening and over the door, the means whereby the door and tray are connected to move together in this way being not necessary to describe herein in detail.

45 Releasable locking means for the door is provided, the same comprising the spring-held latch 19, pivoted to front wall 2, which normally holds the door closed, and a manually rotated member for moving the latch clear of the door, this member comprising a spindle 20 journaled in wall 2 and having an arm 20^a to engage the latch and a knob 20^b. This means, however, cannot be operated until the customer has deposited 50 the proper coin or coins, as will appear.

The fixed upper portion 21 of a coin-chute, whose intake opening is indicated at 21^a in Fig. 1, is provided at the back of front wall 2, this discharging into another chute-portion, as will appear, which is adapted to support temporarily a coin in the position indicated at A in Fig. 4 so that said coin in part occupies chute-portion 21, which has a vertical slot indicated at 21^b, Fig. 3. When a coin is present at A it intervenes between a cam 22 on spindle 20 and a pawl 23 pivoted on a pin 24 and pressed inward by a spring 23^a, said cam and pawl being received by the slot; if the spindle is turned the cam, by wiping against the coin, represses it and consequently the detent formed by the pawl, which thus permits the spindle to complete the movement necessary to move the latch and release the door. If no coin is present opening of the door is prevented because full 60 turning movement of the spindle is then obstructed by the detent or pawl.

65 The coin-controlled controlling mechanism is constructed so that the door cannot be released unless a coin of a predetermined size, as a nickel, is used and a predetermined number of such coins are deposited; provision is also made for the return of coins not earned. To these ends the fixed chute-portion 21 debouches into a lower chute-portion formed in part by a (normally) fixed plate 25 and in part by a channel-plate 26 adapted to swing away from plate 25 on the pin 24 as a pivot but normally urged toward the same by the spring 23^a. Plate 70 25 has tapped into it at different elevations screws 27 whose inner ends are pointed (Fig. 7) and form stops for the coins. We make use of these stops for supporting a coin in the position A, and according as one, two, 75 three or four coins are necessary for unlocking the door-latch-releasing means the first, second, third or fourth stop is screwed fully in and the rest are screwed back or withdrawn (except, as will appear, the 80 fourth or lowest stop is always screwed in). The channel-plate 26 has at the back, opposite the lowest screw 27, an outlet 26^a, Figs. 3 and 6, arranged at the same level as the upper or cam-inlet end of an inclined chute 28 which discharges into a coin-box 29. In the normal position of the channel-plate this outlet is opposed by the inner wall of the chute 28 so that no coin could 85 pass into the latter (Fig. 6); but if the 90 95 100 105 110

channel-plate is shifted in the direction of the arrow in Fig. 6 the coins can enter the chute 28, it thus acting as a receiving member for the coin. This shifting of the channel-plate is effected by the arm 7^b of the door (when the latter falls) engaging, cam-fashion, the inclined face of a toe 26^b at the lower end of the channel-plate. If, then, the proper number of proper coins has been deposited in the apparatus according to the setting of the stops 27 the door may be released by the turning of knob 20^b and its falling will result in the coins being deposited in the coin-box. As explained, the stops 27 afford means for sustaining a predetermined number of coins so that one of them controls the means for releasing the door; and it may be remarked that when the channel-plate shifts away from plate 25 it affords clearance between it and that stop 27 which is supporting a coin or a stack of them to permit the coin or coins to pass, and that it is to assist the coins clearing the stop actually functioning as such that said stops have their ends pointed. The delivery of the coins is normally as already described, or into the coin-box, but the mechanism contemplates also the following:

Plate 25 is hinged as shown in Fig. 2 on a vertical axis at the back thereof. It has connected with it a rearwardly extending rod 30. If for any reason a coin or coins are to be returned the customer notifies the attendant and the latter by pulling on the rod shifts plate 25 and hence stops 27 from the channel-plate; the coins then freely pass the lowest stop and into the pocket 26^c, whereupon plate 25 is returned to normal position.

In the present example, where the chute structure 28 receives the coins laterally from the chute structure 26, it happens that because the former normally opposes the outlet 26^a of the latter it is a factor in supporting the stack of coins with one in the position A in those instances where the maximum number of coins (here four) is required to effect release of the locking means. We therefore claim this coaction of the two chute structures 26 and 28 in their function of supporting the stack so that one will be in the controlling position A, without being limited as to which of the structures is moved to bring the inlet of the receiving structure 28 and the outlet of the structure 26 into registry so as to free the coins or what causes such movement.

31 is simply a light to illuminate the interior of the case through a hole 32.

Having thus fully described our invention what we claim and desire to secure by Letters Patent is:

1. In a coin-controlled apparatus, means to be manually moved having a cam surface, a detent arranged to obstruct the movement

of the first means beyond a predetermined limit and movable to clear the same, and means to receive and support a coin between said cam surface and detent in position for the cam surface to transmit motion to the 70 detent on initial movement of the first means whereby to clear the detent therefrom and permit said movement to said limit.

2. In a coin-controlled apparatus, means to be manually rotated having a cam surface, a detent arranged to obstruct the rotation of the first means beyond a predetermined limit and movable to clear the same, and means to receive and support a coin between said cam surface and detent in position for the cam surface to transmit motion to the detent on initial rotation of the first means whereby to clear the detent therefrom and permit said rotation to said limit.

3. In combination, a supporting structure, 35 a closure movable therein, coin-controlled releasable means normally locking said closure against movement, and a chute to receive a coin for controlling said means and including opposite members one of which has a 90 stop coacting with the other member to support the coin in controlling position and one of which is shiftable from the other to release the coin from said stop, said shiftable member being adapted to be shifted by 95 the closure on release and movement thereof.

4. In combination, a supporting structure, a closure movable therein, locking means for the closure manually movable to release the same, a detent arranged to obstruct the 100 movement of the locking means short of release of the closure and movable to clear the same, and a chute to receive a coin and including opposite members one of which has a stop coacting with the other member to support the coin between the locking means and detent in position to transmit motion from the locking means to the detent on initial movement of the former whereby to clear the detent therefrom and permit 105 said locking means to complete the movement necessary to release the closure, one of said chute members being shiftable from the other to release the coin from the stop and being adapted to be so shifted by the 110 closure on release and movement thereof.

5. In combination, a supporting structure, a closure movable therein, coin-controlled releasable means normally locking said closure against movement, means to receive 120 a coin for controlling the first means and including, with a chute member to contain the coin in controlling position and having a coin-outlet, a coin-receiving member normally obstructing said outlet and co-operative with the chute member to support the coin in the latter in said position and having a coin-inlet to register with said outlet and receive the coin therefrom, one of said members being shiftable to bring 125 130

said out-let and coin-inlet into registry with each other.

6. In combination, a supporting structure, a closure movable therein, coin-controlled releasable means normally locking said closure against movement, means to receive coin for controlling the first means and including, with a chute member to contain the coin in controlling position and having a coin-outlet, a coin-receiving member normally obstructing said outlet and cooperative with the chute member to support the

coin in the latter in said position and having a coin-inlet to register with said outlet and receive the coin therefrom, one of said members being shiftable to bring said outlet and coin-inlet into registry with each other and being adapted to be so shifted by said closure on release and movement thereof. 20

In testimony whereof we affix our signatures.

CARMELO DI MARTINO.
EDWARD LINDQUIST.
